UNITED STATES PATENT OFFICE.

CHARLES P. GROUT, OF NEW YORK, N. Y.

DENTAL ENGINE.

SPECIFICATION forming part of Letters Patent No. 236,326, dated January 4, 1881.

Application filed June 24, 1880. (Model.)

To all whom it may concern:

Be it known that I, CHARLES P. GROUT, of the city of New York, in the county and State of New York, have invented certain new and 5 useful Improvements in that class of machines for transmitting motion commonly known as "Dental Engines," of which the following is a specification.

One of my improvements consists in the 10 combination, in a dental engine or machine, for transmitting motion, of a base, a standard, a driving-wheel supported in said standard, and a universal joint forming a connection between the said base and standard, and 15 preferably, also, a clamping device for securing said standard in different positions.

Another of my improvements consists in the 20 combination, in a dental engine, of a standard, a driving-wheel supported in said standard, and having a crank attached thereto, a treadle adapted to be adjusted around said standard at different angles thereto, and a rod forming a direct connection between said treadle and 25 crank.

Another of my improvements consists in the 30 combination, in a machine for transmitting motion, of a base comprising an arc-shaped treadle-support, a treadle fitted upon said support, a driving-wheel and crank, and a rod forming a direct connection between the treadle and crank, the whole arranged so as to permit the horizontal adjustment of the treadle along said guide.

Three of my improvements relate to those 35 machines in which the upper portion of the standard is hinged or pivoted relatively to the lower portion and a spring is employed for bringing the standard automatically back to a vertical position when desired.

One of such improvements consists in the 40 combination, with such a standard, of a stationary clamping-plate, a spring-actuated plate or piece, and a clamping-screw carried by the standard, whereby facility is afforded 45 for holding the upper part of the standard at an angle to the lower part thereof by friction, or by securely clamping it in position.

Another of such improvements consists in a novel means whereby the upper or hinged

portion of the standard may be locked to or 50 released from the spring which tends to bring it to a vertical position.

The third of such improvements consists in a novel means for adjusting the power of the above-mentioned spring. 55

Other improvements consist in the combination of two shafts, two hinged frames comprising bearings for said shafts, pulleys upon said shafts for the reception of a band, and guide-pulleys, over which said band is deflected as the frames are turned relatively to each other to bring the shafts toward a position in line with each other; also, in a novel arrangement and construction of hood attached to said frames for concealing the pulleys and band. 60

Other of my improvements consist in various combinations of parts and details of construction embodied in the upper part of the machine, whereby a greater range of adjustment is secured, and which are to be herein-after fully described. 70

In the accompanying drawings, Figure 1 represents a side view, partly in section, of a machine embodying my invention. Fig. 2 represents a side view thereof, at right angles to Fig. 1, and also partly in section. Fig. 3 represents a horizontal section through the standard of the machine, at about the center of the driving-wheel bearing. Fig. 4 represents a detail view of the treadle, connecting-rod, and crank. Fig. 5 represents a detail view, herein-after to be explained. Fig. 6 represents a side view of the two hinged frames, with a hood of modified form attached thereto; and Figs. 7 and 8 represent detail views, upon an enlarged scale, of a modified arrangement of guide-pulley for use in connection with said frames. 80

Similar letters of reference designate corresponding parts in all the figures. 90

A designates the base of the machine, to which is secured the standard, consisting of a lower portion, B, and an upper portion, B'. 95

C designates the driving or fly wheel, mounted in bearings in the part B of the standard, and in the present example of my invention the shaft of said fly or driving wheel forms the

pivot which supports the upper portion, B', of the standard, and upon which the latter may turn.

As clearly shown in Figs. 1 and 2, the standard is connected to the base by a universal or ball-and-socket joint, D, which may be tightened by a lever, a, so as to hold the standard at an angle relatively to the base. Though a ball-and-socket joint is preferable, a simple 10 knuckle-joint might be used.

To the shaft of the driving-wheel C is attached a crank, C', which is actuated by a treadle, C², through a connecting-rod, C³. To adapt the treadle and rod for operating the 15 crank when the standard is swung out of a vertical position, I attach the said connecting-rod to the crank by a ball-and-socket-joint, b, and to the treadle by inserting said rod in a socket, c, attached to the treadle, wherein it 20 may be secured by a set-screw, d. The connecting-rod C³ is composed of two pieces connected by a piece, C⁴, which comprises two sockets for the reception of balls upon the ends of the pieces forming the connecting-rod 25 and connecting them together. The piece C⁴ is pivoted at e to the lower part of the standard, so as to serve as a radius-link.

In order to enable the operator to adjust the treadle into convenient position for use, I attach to the base A an arc-shaped treadle-support, A', upon which the treadle may be shifted horizontally at different angles relatively to the standard, the connecting-rod C³ forming a 30 direct connection between the crank and treadle in whatever position the latter may be adjusted to. In the present instance a foot or block, f, is arranged to slide upon said support, and the treadle is hinged to said block or foot.

40 E designates a spring employed to bring the upper portion, B', of the standard back to a vertical position after it has been deflected in either direction.

In order to hold the upper portion of the 45 standard in any desired position, and prevent its return by the spring E, I employ a stationary arc-shaped or segmental plate, F, and provide the said portion B' of the standard with a clamping-screw, g, which may be turned to 50 lock the upper portion, B', of the standard at any position relatively to the lower portion thereof.

In lieu of employing the screw g to clamp the portion B' of the standard at an angle to the lower portion, I may employ a plate or piece, g', adapted to be pressed against the clamping-plate F by the pressure of a spring, g², and thus effect the same result by the 55 friction of the piece g' against the clamping-plate F, as shown in Fig. 2.

In order to adjust the spring E to the exact 60 extension required, I employ a sheath, E', adapted to be adjusted up and down upon said spring, and forming an auxiliary spring of much greater strength than the spring E. When the sheath or auxiliary spring is moved

upward the power or tension of the spring is increased, but when moved downward the tension thereof is diminished.

In some cases it may be desired to dispense 70 with the spring-power for raising the upper part of the standard—as, for instance, when it is desired to use the machine for a long time with the part of the standard inclined, I connect the spring E to a socket or sleeve, G, fitting upon the upper portion, B', of the standard and adapted to slide up and down thereon. When it is desired to disconnect the spring, the said sleeve or socket is raised into the 75 position shown in dotted outline in Fig. 2. 80

Supported upon the upper end of the portion B' of the standard is a frame, H, fitting upon the standard, and secured in place by a set-screw, h. The frame H comprises a socket, H', to the interior of which a sleeve, i, is 85 fitted, and is provided with a set-screw, j, for holding the sleeve in any position after it has been vertically adjusted.

I designates a frame or yoke comprising 90 bearings for a cone-pulley, I', and having a shank or stem, k, fitting in the sleeve i. The frame or yoke I is composed of two pieces adapted to swing independently of each other upon the shaft of the cone-pulley I' as a pivot.

I² designates guide-pulleys, supported upon 95 a shank or stem, l, which fits the interior of the standard B', and is adapted to be secured in any vertical position by the screw h, which holds the frame H in place.

It is obvious that when it is desired to pass 100 the band J over any particular step of the cone-pulley I' the sleeve i must be raised or lowered in the socket H', so as to bring the step of said pulley opposite the upper periphery of the guide-pulleys I².

To the yoke or frame I is hinged a second yoke or frame, K, which furnishes a bearing 105 for the shaft K', to which motion is imparted from a pulley, m, upon the shaft of the cone-pulley I', by a band, n, passing around guide-pulleys n' and over a pulley, n², upon the end 110 of the shaft K'. This affords provision for turning the shaft K' into a position in line with the cone-pulley I', or into a position parallel therewith, or at any angle between said 115 two extreme positions. When the shaft K' is turned up into line with the pulley I' a greater length of band n is required than when it is turned down into a nearly-parallel position, and to prevent undue straining of the band 120 the guide-pulleys n' are supported upon studs projecting from the pin or pivot o, (see Fig. 2,) which hinges the frame or yoke K to the frame or yoke I, the said studs being eccentric to the center of the pin o. When so constructed the lower side of the periphery of the 125 guide-pulleys n' is nearly coincident with the center of pin o, and in turning the frame K over parallel with the frame I the belt or band n is not strained. This same result may be 130 accomplished by mounting the pulleys n' on studs n³, separate from the hinge-pin o, as

shown in Figs. 7 and 8, and in such case the studs n^3 are arranged to slide in bearings n^4 , and springs n^5 are employed to press them outward from the centers of the shaft K' and of the cone-pulley I' when the two are in line with each other. As the band n is drawn over the pulleys n' by the swing of the frame K , the pulleys n' are moved inward against the pressure of the springs n^5 , and the straining of the band obviated.

In order to partly support the shaft K' and connections, when turned outward to an approximately horizontal position, as shown in Fig. 1, I employ a spring, p , coiled around the pin o , uniting the frames I and K , as represented in Figs. 1 and 5.

$L L'$ designate two frames like the frames I and K , hinged together in the same way. The frame L is loosely fitted upon the shaft K' , and the frame L' supports the shaft M , which is intended to carry a tool.

Motion is imparted from a pulley, q , on the shaft K' by a band, r , passing around guide-pulleys s and over a pulley, t , upon the shaft M , the guide-pulleys being similar to the pulleys n' , and supported in the same way. The shafts K' and M are free to turn in their bearings in the frames supporting them, and are furnished with collars u , for preventing their shifting lengthwise.

In order to prevent the hair or whiskers of an operator from catching in the belts or bands n and r , I employ guards or hoods O , attached to each of the frames I K L L' , and serving to conceal the pulleys over which the bands n and r pass, as clearly shown in Fig. 5.

In lieu of the form of hood shown in Figs. 1, 2, and 5, I may employ a hood composed of sections O' , as shown in Fig. 6, the two end sections being permanently attached to the frames I and K , and the several sections being so constructed that they telescope one within another when the frames are swung together from the position shown in Fig. 6. The several sections may be connected at theirlapping edges by pins, and working in slots, so that the separation at the edges is prevented.

By my invention I provide a dental engine in which varied adjustments of the several parts are readily effected, and a very wide range of adjustment secured, which are the great aims in constructing such a machine.

Although my improvements are here shown as embodied in a dental engine, I do not intend to limit them to machines for dental use only; but they may be embodied in similar machines for other purposes.

I am aware that I am not the first inventor of a dental engine comprising a tilting upright and means for securing it in a normally inclined position, and I do not, therefore, claim this as my invention.

What I claim as my invention, and desire to secure by Letters Patent, is—

1. The combination, in a dental engine, of

a base, a standard, a driving-wheel supported in said standard, and a universal joint forming a connection between said base and standard to permit the tilting of the latter from a vertical position in any direction, substantially as specified.

2. The combination, in a dental engine, of a base, a standard, a driving-wheel supported in said standard, a universal joint forming a connection between said base and standard to permit the tilting of the latter from a vertical position in any direction, and a device for rigidly securing said standard in different positions to which it may be adjusted, substantially as specified.

3. The combination, in a dental engine, of a base, a standard, a driving-wheel and crank supported in said standard, a treadle, a ball-and-socket or universal joint between the base and standard, and a rod with a ball-and-socket or universal connection between said treadle and crank, substantially as specified.

4. The combination, in a dental engine, of a standard, a driving-wheel supported in said standard and having a crank attached thereto, a treadle adapted to be adjusted around said standard at different angles thereto, and a rod forming a direct connection between said crank and said treadle, substantially as specified.

5. The combination, in a dental engine, of a driving-wheel, a crank attached thereto, a base comprising an arc-shaped treadle-support, a treadle adapted to be adjusted horizontally upon said support, and a rod forming a direct connection between said treadle and said crank, substantially as specified.

6. The combination of the base A , the arc-shaped treadle-support A' , the standard $B B'$, the ball-and-socket joint D , the driving-wheel C , the crank C' , the treadle C^2 , rod C^3 , and radius-link e , all substantially as specified.

7. The combination of the standard $B B'$, the stationary clamping-plate F , the clamping-screw g , the plate g' , and spring g^2 , substantially as specified.

8. The combination, in a dental engine, of a standard composed of a lower and an upper portion hinged together, a spring attached to one portion and engaging with another for holding the two portions in line one with the other, and a sheath longitudinally adjustable on said spring for increasing or diminishing its tension, substantially as specified.

9. The combination, in a dental engine, of a standard composed of a lower and an upper portion hinged together, a spring attached to the lower portion, and a socket adapted to slide longitudinally upon the upper portion, and engaging with said spring, whereby a convenient means is afforded for disconnecting the spring from the upper portion, substantially as specified.

10. The combination, in a dental engine, of a driving-wheel, a vertically-arranged cone-pulley, guide-rollers for deflecting a band from

the driving-wheel to the cone-pulley, and a frame or yoke supporting the cone-pulley and adapted to be vertically adjusted for bringing any step of said pulley opposite the guide-pulleys, substantially as specified.

11. The combination of the tubular socket H' , the vertically-adjustably sleeve i , the frame I , provided with the stem k , fitting in said sleeve, and the cone-pulley supported in the frame I , substantially as specified.

12. The combination of the frames I K , hinged together, and the spring p , arranged substantially as specified.

13. The hinged frames I K , and the hood composed of sections O' , the two end sections being permanently attached to the said frames,

and the others adapted to telescope or slide one within the other, substantially as specified.

14. The combination of two shafts, frames I K , hinged together and comprising bearings 20 for said shafts, pulleys m n^2 , a band, n , passing around said pulleys, and guide-pulleys n' for said band, substantially as specified.

15. The combination of the frames I K , hinged together by the pin o , the pulleys m n^2 , 25 and the guide-pulleys n' , supported upon movable studs n^3 , and springs n^5 for bearing upon said studs, substantially as specified.
